TUBE ASSEMBLING METHOD

Arthur L. Parker, Cleveland, Ohio

Original application April 29, 1938, Serial No. 205,102. Divided and this application November 20, 1939, Serial No. 305,371

2 Claims. (Cl. 29—148.2)

This invention relates generally to tube couplings and has for an object to provide a novel method for securing the tubes of said couplings in the sleeves which surround and protect them and serve in part to clamp them in place in complete couplings, and for flaring the tube ends during the formation of the assemblies.

In the formation of certain forms of tube couplings, of which my prior Patent 1,893,442, issued January 3, 1933 forms an example, it is customary to provide the tubes with flared ends and to clamp said ends between opposing coniform male and female clamping surfaces, the latter of which are formed in sleeves which are intended to snugly surround the tubes and protect them from damaging vibrations and which include shoulders engaged by nuts adjustable along the axis of the tubes and sleeves to seat the sleeves in clamping engagement with the flared tube and the opposing male clamping surfaces. When any appreciable clearance is permitted between the sleeves and the tube portions which they surround, vibration of the coupled tubes is permitted and breakage often results. In my present invention I seek to remedy these evils by providing a novel method of preparing tube ends for the formation of tube couplings consisting in first bringing a tube end and its surrounding protective sleeve into permanent, intimate wall to wall contact and then flaring the end portion of the tube against an opposed clamping surface of said sleeve.

Therefore, it is an object of the invention to provide a novel method of forming a tube element assembly comprising a tube to be coupled and a protective sleeve surrounding the tube and including a flared portion opposed to the tube end, said method comprising the steps of bringing the opposed walls of the tube and sleeve into permanent intimate contact and in flaring the tube end into the flare of the sleeve.

With these and other objects in view which will more fully appear, the nature of the invention will be more clearly understood by following the description, the appended claims, and the several views illustrated in the accompanying drawing.

This case is a division of my co-pending application Serial No. 205,102, filed April 29, 1938.

In the drawing:

Figure 1 is a fragmentary sectional view of a tube end and sleeve assembly with an expanding device shown freely inserted in the tube end preparatory to expanding said tube.

Figure 2 is a view similar to Figure 1 with the

tube expanded into the sleeve but with a portion only of the expanding device being shown in action.

Figure 3 is a view similar to Figure 2 and illustrates the completion of the step of flaring the expanded and clamped tube.

Figure 4 is a view similar to Figure 3 and illustrates the flaring head released for movement independent of the adjusting nut.

In Figures 1 through 4 in the drawing, I have illustrated steps in the formation of a tube assembly embodying the invention. The tube of this assembly is designated 17. In practicing this method a sleeve 18 is slipped over the end of the tube 17, the tube is then expanded to engage the sleeve in permanent, intimate wall to wall contact so as to eliminate all space which would permit the tube to vibrate independently of the protective sleeve, and the end of the tube is then flared by use of suitable apparatus an example of which is disclosed herein and forms the subject matter of the co-pending application hereinbefore referred to. The sleeve 18 used in this method is provided with the usual flare 19 and clamping shoulder 20.

The manner of using the apparatus in the practicing of the above mentioned method of forming tube assemblies is illustrated in the somewhat diagrammatic Figures 1, 2, 3 and 4. In Figure 1 a tube 17 is properly mounted in its cooperating protective sleeve 18 and the expanding chuck 21 is inserted into the end of the tube.

In Figure 2 the expanded condition of the tube is illustrated. In other words, the chuck has been expanded to enlarge the wall portion of the tube and force it into permanent, intimate wall to wall contact with the surrounding sleeve 18. This is accomplished by turning the handle member 22 about the axis of the rod 23, causing the rod 40 to move longitudinally in the sleeve 24 and force the elements 25 and 26 toward each other to thereby expand the chuck sleeve 21 and accomplish the tube expansion just described. By turning the handle member 27 about its axis so as to cause the threaded end thereof to tightly grip the nut 28, and by then swinging the handle member 27 about the axis of the rod 23, the nut 28 will be made to force the head 29 and the tube end flaring portion 30 thereof downwardly into the 50 end of the tube 17 to flare the same. The completion of the flaring function is shown in Figure 3 of the drawing. The downward movement of the flaring head 29, 30 can be effected by completely rotating the handle member 27 about the axis of the rod 23 while holding the handle mem-

bers 22 and 31 stationary, or the handle member 27 can be moved in a partial rotation, then unscrewed slightly to relieve the clamped condition of the nut and rotated partially in the reverse direction, and then re-clamped and rotated again in the first stated direction in successive cycles so as to set the flaring portion step by step if desired.

After the expansion and flaring of the tube has been completed as shown in Figure 3 of the drawing, the handle member 27 can be turned to free the clamped relation of the end thereof with the nut 28 as indicated at 32 in Figure 4, thus freeing the head 29, 30 for rotation about the nut 28 without imparting movement to said nut. With the parts thus adjusted, it is possible to oscillate the head portion 30 within the flared end of the tube to burnish the flared surface of the tube intended to engage the male seat in the finished coupling.

In the foregoing description, I have disclosed a novel tube assembly and method of forming the same in which the tube to be coupled is brought or expanded into permanent intimate wall to wall contact with its surrounding protective sleeve and then flared to prepare it for ultimate coupling.

It is, of course, entirely feasible to bring the sleeve and tube into intimate wall to wall contact by contracting the sleeve around the tube by radially applied pressure, rather than by expanding the tube into the sleeve.

I claim:

1. The herein described method of preparing tubes for coupling purposes which comprises, fitting over the end of the tube to be coupled a protective sleeve having a flared end, expanding the tube into permanent intimate wall to wall contact with the sleeve by pressure applied by a single agency and in the radial outward direction only, said single pressure application being effective for the two-fold purpose of effecting permanent union of said tube and sleeve and holding them against longitudinal movement, and while maintaining said pressure application flaring the end of the tube against the flare of the sleeve.
- 5 2. The herein described method of preparing tubes for coupling purposes which comprises, fitting over the end of the tube to be coupled a protective sleeve having a flared end and of a diameter for closely but loosely surrounding said tube, expanding the tube throughout a portion of the length of the sleeve and adjacent the flared end of the sleeve into permanent intimate wall to wall contact with the sleeve by pressure applied by a single agency and in the radial outward direction only, said single pressure application being effective for the two-fold purpose of effecting permanent union of said tube and sleeve and holding them against longitudinal movement, and while maintaining said pressure application flaring the end of the tube against the flare of the sleeve.
